[57] **CLAIM**

The ornamental design for a bedstead, as shown and
described.

DESCRIPTION

FIG. 1 is a left front perspective view of a bedstead showing
our new design;

FIG. 2 is a front elevational view thereof;

FIG. 3 is a side view, the opposite side being a mirror image
of the side shown; and,

FIG. 4 is a rear view of the footboard of the bedstead.

The bottom and rear views are not shown and form no part
of the claimed design.
